John N. Covert, Lombard, Ill., assignor to Union Special Machine Company, Chicago, Ill., a corporation of Illinois

Filed Jan. 17, 1956, Ser. No. 559,604

24 Claims. (Cl. 112—256)

This invention relates to improvements in sewing machines by virtue of which such machines may be operated more efficiently and at higher speeds than has heretofore been possible.

Toward the foregoing end, the machine embodies improved means for insuring proper lubrication of the bearing surfaces of various relatively moving parts. The machine to which the invention is directed is provided with a hollow frame having a work supporting base, a vertical standard, an overhanging arm and a needle bar carrying hollow head at the end of said arm. The invention is particularly concerned with a lockstitch machine of this character provided with a horizontal axis rotary hook in the base.

An important feature of the invention is the provision of a single, relatively large lubricant reservoir in the base of the frame from which lubricant is supplied to all of the important bearing surfaces in the machine. This reservoir extends beneath a substantial portion of the work supporting surface of the base and beneath the vertical standard of the frame. In the preferred construction the machine is provided with a rotary drive shaft extending longitudinally of the base and another rotary drive shaft extending longitudinally of the overhanging arm, these shafts being interconnected by a ribbed or toothed belt within the vertical standard cooperating with a toothed pulley or sprocket on each of the shafts. Power is preferably supplied to the machine through a pulley secured to the upper shaft outside of the machine frame.

One aspect of the invention involves the provision of means adjacent the top of the vertical standard for collecting oil dispersed as a mist by the rapid movement of the above mentioned belt through the body of oil contained in the lubricant reservoir. A portion of the oil so collected is delivered through a special conduit extending longitudinally of the overhanging arm into the needle head and to bearing means for the upper drive shaft. A wick member is provided in the conduit to serve as a lubricant storing means so that lubricant is available for immediate delivery to parts within the head and a bearing for the upper shaft as the machine is put into operation. The arrangement is such as to insure the delivery of an adequate but not excessive amount of lubricant to the shaft bearing and to the parts requiring lubrication within the needle head at all times. Provision is also made for the return to the main reservoir of any excess lubricant delivered through the special conduit. Such return of excess lubricant is accomplished in part from the conduit itself, prior to delivery to the surfaces to be lubricated, and in part by special means for returning some of the oil actually delivered to the parts requiring lubrication. Various expedients are employed for the latter purpose, including an automatic self-priming siphon for returning excess lubricant from a sump at the bottom of the needle head and an arrangement for returning directly to the reservoir certain of the lubricant

2

which seeks to escape through a necessary opening in the front wall of the needle head through which a thread take-up arm extends.

Another special feature involves the provision of lubricant collecting means within the needle head adapted to deliver to certain parts within the head some of the lubricant dispersed as a mist within the head. This collecting means, moreover, is so constructed and arranged as to prevent the discharge of lubricant mist through certain openings necessarily provided in the walls of the needle head.

As another feature of the invention there is provided in the needle head, as a part of a rotary member therein, a device for collecting some of the lubricant mist within said head and directing the same away from the above mentioned thread take-up arm and toward the means in said head for delivery of lubricant to points requiring lubrication.

A further special feature is the provision of readily accessible means for stopping the automatic delivery of lubricant into the needle head while continuing the delivery of lubricant to other surfaces within the machine. This is desirable to guard against the soiling of certain special types of work as the result of the lubricant mist normally created within the needle head. Specifically the improved cut-off means comprises a plurality of lubricant conducting wick elements in series and means for disengaging one of the wick elements from another. The arrangement is such, moreover, that the main wick in the conduit within the overhanging arm still continues to deliver lubricant to the shaft bearing, through a Y branch, when delivery to operating parts within the head is cut off. When the control means is operated to shut off the automatic delivery of lubricant into the needle head a normally closed passage for the introduction of a small amount of oil by hand from an oil can is rendered accessible for this purpose.

Still another feature of the invention is the provision of improved means for delivery of an accurately controlled amount of lubricant from the main reservoir to the raceway of the rotary hook of the lockstitch machine. The arrangement is such that the quantity of lubricant supplied to the raceway may be quickly changed, to provide just the right amount of lubricant to meet the requirements of the hook, by the adjustment of a member which is readily accessible. Determination of the rate of delivery of oil from the main reservoir is in accordance with the effective length of a capillary conduit through which the oil is passed, the length of said conduit being determined by the relative positions of two rotary but normally stationary members of capillary character. The angular adjustment of one of said members predetermines the length of the capillary conduit and thereby regulates the quantity of oil delivered. One of the rotary members is partially immersed in the oil in the reservoir and the arrangement is such that oil picked up by said member is delivered to a selected point on the other. Due to the rotary character of the two members wear of the contacting surfaces, upon relative adjustment, is eliminated. Simple means forming part of the devices for adjusting at least one of said members serve to limit the extent of relative adjustment of said members. Certain parts within the reservoir serve to create a lubricant mist therein for the lubrication of various parts. Provision is made, however, for preventing delivery of this mist to the capillary member which controls the quantity of lubricant delivered to the hook raceway.

Other objects, features and advantages of the invention will appear from the detailed description of an illustrative form of the same which will now be given in

conjunction with the accompanying drawings, in which: Fig. 1 is a view, largely in longitudinal, vertical section but partly in elevation, of a machine embodying the invention;

Fig. 2 is an end elevational view of the machine as seen from the left in Fig. 1, with a cover plate removed and a hood shown in section;

Fig. 35 is an end view of the hook shaft.

Referring now to the drawings, the invention has been disclosed as embodied in a lockstitch machine having a frame provided with a work supporting base 10, a vertical standard 11, and an overhanging arm 12 terminating in a needle head 13. A closure plate 14 is provided across a major portion of the bottom of the machine, including that part beneath the vertical standard and a substantial part beneath the work supporting surface of the base. This closure plate, in conjunction with vertical walls of the frame and the work supporting top of the base, provides a relatively large lubricant reservoir 15 adapted to retain a body of lubricant as shown in Fig. 1. The closure plate is secured to the bottom of the frame by means of a pair of screws 16 which pass through upwardly extending bosses 17 on the plate. One of the screws is threaded into a downwardly extending, intermediate wall 18 of the base of the frame, while the other screw is threaded into another intermediate, downwardly extending wall 19 of the frame. The arrangement of the walls and bosses is such that the lubricant reservoir is divided into several sections, but the walls 18 and 19 have passages therethrough so that the lubricant may flow freely from one section to the other to maintain the same level in all. Around the periphery of the plate 14 is an upstanding flange 20 (Figs. 1 and 13) having a groove 21 in its upper surface. This groove is arranged to receive and retain a continuous band-like gasket 22, preferably formed of neoprene and preferably of circular cross-section. This gasket is squeezed against the bottom surfaces of the walls of the frame which surround and serve to enclose the lubricant reservoir 15. Gasket 22 thus provides an oil tight seal between the main body of the reservoir and the closure plate 14. As best shown in Fig. 1, the bottom wall of the closure plate 14 is preferably curved slightly and, as shown in Fig. 13, is provided with upstanding ribs 23. Foot elements 24 extend downwardly from the plate 14 to permit the machine to rest firmly on a table top or the like. The formation of the closure plate 14 is such that a minimum area of its top surface requires machining in order to cooperate properly with the bottom surfaces of the walls of the main portion of the machine frame.

Extending longitudinally of the overhanging arm 12 is a rotary drive shaft 25 suitably journaled at its right end in a bearing sleeve 26 carried by the end wall of vertical standard 11 and journaled adjacent its left end in a bearing sleeve 27 carried by a partition wall 27a which serves to separate the needle head from the chamber within the overhanging arm. At its right end the shaft 25 has secured thereto a combined handwheel and pulley 28 through which the shaft may be turned by hand and also driven from a suitable power source. At its left end shaft 25 extends into the needle head and within the latter carries a crank member 29 of suitable construction, such as that disclosed in the patent to Sauer, No. 2,324,598, granted July 20, 1943. This crank member carries a crank pin 31 (Fig. 2) cooperating with a strap at the upper end of a pitman or link 32. A needle bearing unit is preferably provided between the crank pin and the strap of the link 32. At its lower end the link 32 is pivotally connected with a block 33 clamped upon a needle bar 34 arranged for vertical reciprocation in bearing sleeves 35 and 36 (Fig. 1). Needle bar 34 carries at its lower end a needle 37 arranged for reciprocation through the throat plate of the work supporting base of

the machine. Another crank pin 38 carried by the crank member 29 is arranged to receive the strap portion of a lever 39 having an outwardly extending arm 40 which passes through a slot in the forward wall of the needle head and is provided with an eyelet to receive the needle thread. Arm 40 is a take-up member for the needle thread. A needle bearing unit is preferably provided between the crank pin 38 and the strap of lever 39. At about its mid-point the lever 39 is pivotally connected with an arm 41 rockably mounted on a stud 42 carried by the needle head. The arrangement is such as to provide the desired up and down movements of the take-up arm 40 as the crank element 38 is carried around a circular path by rotation of shaft 25.

Cooperating with the needle in stitch formation, beneath the work supporting surface of the base 10 of the machine, is a rotary hook having a rotary component 43 and a stationary bobbin retaining member 44. The rotary component is secured to a shaft 45 journaled in a bearing sleeve 46 carried by a downwardly extending wall 47 of the base and also by the left wall (Fig. 1) of the lubricant reservoir. Shaft 45 extends into the reservoir and within the latter carries a pinion 48 which meshes with a gear 49 secured to a rotary drive shaft 50 which extends longitudinally of the base of the frame. Pinion 48 and gear 49 are such as to impart two revolutions to the rotary component 43 of the hook for each revolution of the shaft 50. This shaft is journaled in suitable bearings provided in the base of the frame, one of these being shown at 51 in Fig. 1. Within the base of the vertical standard there is secured to the shaft 50 a pulley 52 which is connected by a belt 53 with a pulley 54 secured to the shaft 25. To insure a positive drive connection between the two shafts the belt 53 is provided with ribs or teeth on its inner face arranged to cooperate with grooves or teeth in the surfaces of the pulleys 52 and 54. Moreover, the belt 53 is formed of an oil resistant material, such as neoprene, so that it is not adversely affected by the lubricant in the reservoir 15.

Suitable work feeding devices are embodied in the machine and, as illustrated, these may include a four motion feed dog 55 (Fig. 2) having a shank 56 by which it may be adjustably secured to the forward end of a feed bar 57 pivotally mounted by means of a shaft 58 on a feed rocker 59 rockably mounted in the base of the frame about the axis of a pivot 60. Adjacent its forward end the feed bar has a downwardly extending arm 61 with which is pivotally connected a pitman 62 having, at its upper end, a strap portion arranged to cooperate with an eccentric or crank pin at the end of the drive shaft 50 adjacent the point of stitch formation. Rocking movements are imparted to the feed rocker 59 by connections shown in Fig. 3. A stud or rock shaft 63 carried by the feed rocker 59 provides a pivotal connection between the latter and a pitman 64 having at its forward end a strap cooperating with an adjustable eccentric 65. Preferably, as shown, a needle bearing unit is provided between the eccentric 65 and the strap of the pitman 64. The adjustable eccentric may suitably be of the general type disclosed in the patent to Arthur N. Hale, No. 2,718,860, granted September 27, 1955.

Cooperating with the feed dog in advancing the work is a presser foot 66 pivotally mounted upon a shank member 67 secured by a screw 68 to a presser bar 69. The latter, as best shown in Fig. 2, is mounted for vertical movement in a bearing sleeve 70 extending through the bottom wall of the needle head. Adjacent its upper end the presser bar is provided with a laterally extending arm 71 arranged to cooperate with a vertically extending guide slot in the rear wall of the needle head to prevent turning of the presser bar. Means are provided for lifting the presser bar and the presser foot from the work or the work supporting surface of the base whenever desired. This comprises a manually operable lever 72 having a cam formation arranged to cooperate with

an arm 73a extending laterally from a collar 73 slidably mounted on the presser bar. As the rearwardly extending arm of the lever 72 is lifted by the operator, the arm 73a will be lifted into engagement with the arm 71 and will then lift the latter together with the presser bar. Another arm 73b extending laterally from the collar 73 (Fig. 25) serves to cam outwardly a pin 73c, as the collar is lifted, and releases the tension applied to the needle thread by a conventional type of thread tensioning device mounted in the front wall of the needle head. A neoprene gasket 73d surrounding a reduced portion of the barrel of the thread tensioning device provides a lubricant-tight seal for the latter. As best shown in Figs. 2 and 15, a thread guiding element 74, carried by the arm 71 extends through a slot in the forward face of the needle head and is arranged to be lifted and lowered with the up and down movements of the presser bar. A spring 75 normally urges the presser bar downwardly, this spring having its lower end in engagement with the upper surface of arm 71 and its upper end in engagement with a shoulder on a threaded sleeve 76. The latter is provided with a knurled head 77 at the top of the frame by which the tension of the spring may be varied as desired.

Means are also provided for lifting the presser bar by connections from a foot treadle or knee-press. For this purpose a link 78 is pivotally connected at its lower end with the arm 73b and is pivotally connected at its upper end with a lever 79 which extends longitudinally of the overhanging arm and into the needle head. This lever is pivotally mounted by means of a screw stud 80 (Figs. 1 and 4) within a passage 12a in the overhanging arm which communicates with the needle head. Passage 12a is in rear of an enclosed chamber 12b within the overhanging arm, which is in direct communication with the hollow of the vertical standard but is substantially sealed off from the needle head. At its right end the lever 79 has a laterally extending pin 81 which projects outwardly through an opening 12c in the rear wall of the overhanging arm. A link 82 cooperating with a groove adjacent the outer end of the pin 81 receives the upper end of a chain 83, the lower end of which is connected with a hook 84 (Figs. 2 and 5) which extends downwardly through an opening in a lateral extension of the base of the frame and at its lower end is connected with a rock member 85 (Figs. 5 and 6). This rock member is arranged to be rocked by suitable connections from a knee-press or treadle to bring about a rocking movement of the lever 79 which results in the lifting of the presser bar and presser foot.

The machine in accordance with the present invention embodies certain novel and particularly effective devices for insuring proper lubrication of all of the wear receiving surfaces within the overhanging arm and needle head. For this purpose lubricant is withdrawn or impelled from the main reservoir and delivered into the head. As shown in Fig. 1, the pulley 52 and belt 53 are partially immersed in the lubricant within the reservoir 15, i.e. that part which extends below the vertical standard, and upon movement of these parts in the course of operation of the machine there is created a lubricant mist or spray within the vertical standard. A portion of this mist is collected by ribs extending downwardly from the top wall of the standard. Thus a rib 86 is arranged to collect lubricant from the mist and deliver a portion of it to a pocket 87 communicating with the bearing sleeve 26. A felt plug 87a, or the like, is preferably provided in a passage extending through the sleeve 26 and a retainer 26a for the same. This serves to deliver a desirable amount of lubricant to the bearing surface of the sleeve 26. Another portion of the lubricant collected by the rib 86 is delivered by a downwardly extending projection 86a into a trough 88 (Fig. 4) connected with a conduit 89 which extends through the chamber 12b of the overhanging arm to a hollow fitting 90. The latter is fixedly

mounted in the wall 27a which separates the space within the needle head from that within the chamber 12b of the overhanging arm. Within the fitting 90 and extending into the conduit 89 is a wick element 91 which serves as a storage means for a suitable amount of lubricant. This insures immediate supply of lubricant to certain parts on the commencement of operation of the machine after it has been idle. The arrangement, however, is such that the delivery of an excessive amount of lubricant into the needle head is prevented. For this purpose the fitting 90 is provided with a projection 92 which extends upwardly from the bottom wall of the opening through the fitting. This projection forms a wall or dam which serves to prevent the direct delivery of lubricant from the conduit into a pocket 94 at the opposite side of the projection. The only lubricant delivered to the pocket 94 is that conveyed by capillary action through wicking 91. Excess lubricant which may be delivered through the conduit 89 is discharged through an opening 93 in the wall of the fitting 90 which serves to return such excess lubricant to the chamber 12b of the overhanging arm from which it is returned by gravity to the reservoir 15.

Referring now particularly to Figs. 7 and 20, there is provided within the pocket 94 a felt disc 95 which is held against a downwardly bent portion of the wick 91. In engagement with the opposite side of the disc 95 is a loop of a felt element 96 which is retained by a bracket member 97. This bracket member has a vertically extending portion positioned across the end of the fitting 90 and secured to the latter by means of screws 98. Member 97 also has a horizontally extending portion 99 having a downwardly and outwardly extending branch 100 (Figs. 20 to 24). To the latter is secured, by screws or the like, a spring blade 101 which serves to support the upper portion of the felt element 96. On the top of the portion 99 of the bracket is mounted a felt strip 102 having a looped portion extending through the part 99 and into engagement with the top surface of the element 96 in the region thereof carried by the plate 101. Normally the latter retains the felt elements 96 and 102 in firm but yielding engagement. Through the wick system described lubricant is delivered from the storage wick 91 into the needle head for distribution to various parts requiring lubrication within the head. Also it will be noted that a downwardly extending portion 91a (Fig. 7) of the wick 91 passes through aligned openings in the fitting 90, the wall 27a and bearing sleeve 27 into engagement with the surface of the shaft 25 for lubricating the latter. Such lubricant is not excessive since it is delivered only through the capillary action of the wick 91 and therefore little or no lubricant is delivered along the shaft 25 into the needle head.

For the delivery of lubricant from the felt pad 102 to various parts within the needle head, the horizontal portion 99 of the bracket 97 is provided with downwardly extending tubes 104, 105 and 106 through which extend loops of a wick element 107 (Fig. 22). The latter has portions resting upon the upper surface of the pad 102 and picks up lubricant from the latter for delivery to the loops at the lower ends of the tubes. That portion of the wick which extends through the tube 105 is arranged to cooperate with a groove 108 (Figs. 9 and 10) in the top of the strap of the pitman 32 as the latter is carried around by the crank element 31. The bottom of the groove 108 is flat, as shown in Fig. 10, and communicates with a felt plug 109 which extends through the wall of the strap to the roller bearing which cooperates with the crank pin. The wick loop projecting from the tube 104 cooperates in a similar manner with a groove in the strap of the lever 39 which surrounds the crank pin 38. In this way both of the roller bearing units are well lubricated. Similarly the pivot 42 of the arm 41 is lubricated by oil delivered through the wick in tube 106 (Fig. 2). The loop at the lower end of this wick cooperates with a groove 110 (Fig. 21) in the hub of the lever 41 and de-

livers the lubricant to the bearing surface through an opening 111 which may, if desired, be provided with a felt plug. Excess lubricant delivered along the pivot stud 42 for the lever 41 is picked up by a section of wicking 112 which is looped around the stud adjacent the end of the hub and this wick section serves to deliver lubricant to a cavity 114 in a pivot stud 115 at the opposite end of the arm 41 into which the wicking fits. From this cavity the lubricant is delivered through an opening 115a to the bearing surface of the stud 115 about which the take-up lever 39, 40 is rocked.

Provision is made for shutting off the automatic delivery of lubricant into the needle head in the manner described. This, as best shown in Figs. 20 to 24 and 26 to 29, comprises a disc 116 which is accessible at the top of the needle head. This disc has a downwardly extending shank 117, the lower end of which carries a face cam 118 (Figs. 26 and 27) arranged to cooperate with an upwardly extending projection 119 on the spring plate 101. When the disc 116 is in the position indicated in Fig. 27 the spring plate 101 is permitted to lift the felt strip 96 into contact with the loop of the felt pad 102 so that automatic delivery of lubricant to the parts in the needle head is brought about. However, when the disc 116 is turned into the position shown in Fig. 26 the spring plate 101 is depressed to disengage the elements 96 and 102 and thus interrupt the flow of lubricant between these capillary members. At this time a desired amount of lubricant may be delivered into the needle head from an oil can through an opening 120 in the disc which is then aligned with a wick element 121 mounted in an opening through the top of the needle head. The lower end of this element is directly above a portion of the felt pad 102 and serves to deliver a limited amount of lubricant to the latter. On the other hand, when the disc is turned into the position shown in Fig. 27 a small portion of the disc covers the top of the wick 121 to prevent hand oiling. To facilitate turning of the disc 116 it is preferably provided with a diametrically extending rib 122.

The movement of various parts receiving lubricant in the automatic manner described above serves to create a spray or mist within the needle head and some of the lubricant descends to a pocket at the bottom of the head. Means are provided for utilizing certain of this lubricant to lubricate other parts within the head, including the needle bar and its bearing means. For this purpose there is provided, as best shown in Figs. 3, 14, and 16 to 19 inclusive, certain means including a felt strip 123 suitably positioned and held along the front wall of the head. This strip has its lower end within the lubricant pocket at the bottom of the needle head and serves to elevate such lubricant by capillary action for delivery to certain parts in the manner to be explained. The upper end of the strip 123 is held by a clamp element 124 which is secured against the inner face of the front wall of the head by means of a bolt 125 and a nut 126. On the outside of the needle head the bolt 125 serves also to carry a thread guiding element 127. An opening 128 (Fig. 16) is provided through the felt strip 123 to permit the necessary movement of the thread guide 74 which, as previously indicated, is lifted and lowered with the up and down movements of the presser bar. Adjacent the inner face of the strip 123 there is provided a bracket 129 having an upper portion 130 provided with an opening 131 by which the bracket may be secured by a screw (not shown) to the forward wall of the needle head. Bracket 129 has a shelf-like portion 132 which is inclined downwardly from the end of portion 130 both in the direction away from the inner surface of the front wall of the head and in a direction along said wall. This shelf extends over the opening 128 in the strip 123 which it will be understood is aligned with a corresponding opening in the wall of the head. It serves to prevent the direct discharge of lubricant through said opening. At the lower end of the shelf 132 there is provided a relatively thin finger 133

which extends downwardly along the inner face of the strip 123 to hold the latter against the forward wall of the needle head. On the shelf 132 there is provided a felt strip 134 one edge of which is in engagement with the strip 123 and receives lubricant from the latter. Such lubricant includes that collected by the strip 123 from the spray or mist within the needle head and also that which is elevated by the capillary action of strip 123. The strip 134 has a portion thereof looped to provide a downwardly extending part 134a which is held by a spring clamp 135 (Figs. 7, 8, 11 and 16) against the lower portion of the bearing sleeve 36 for the needle bar. It is held by the clamp 135 against a felt block 136 carried within an opening extending through the lower reduced portion of sleeve 36 and thus serves to deliver lubricant to the surface of the needle bar 34.

As shown in Fig. 12 the front wall of the needle head is provided with a vertically extending slot 137 through which the take-up arm 40 extends and is moved up and down. Means are provided for collecting any lubricant which may be thrown through this slot upon movement of the parts within the head. This means comprises a hood 138 secured to the outer surface of the front wall of the head by means of screws 139. Hood 138 extends outwardly from the head, as best shown in Figs. 2 and 3, and has the outer end of the top wall thereof curved downwardly as indicated at 138a. A felt strip 140 is adhesively secured to the under surface of the top of the hood 138 and serves to collect lubricant mist which may be thrown outwardly through the opening 137 in the manner explained. At its inner end the felt strip 140 is folded over and a portion at the bend thereof engages a portion of a wick element 141 which extends through an opening in the top wall of the needle head, through the partition wall 27a and into chamber 12b within the overhanging arm. Wick element 141 is preferably L-shaped as best shown in Fig. 12. It serves to return directly to the main reservoir 15 the lubricant which is collected by the felt pad 140. The amount of lubricant which is thrown through the opening 137 is greatly reduced by the provision of an oil slinger 116a (Figs. 7 and 9) at the outer end of the crank element 31. It is secured to the crank element by a screw 31a and has a conical periphery which tends to throw oil collected by it toward the right, away from the opening 137.

Means are also provided for returning to the main reservoir excess lubricant which accumulates in a pocket 142 in the bottom of the needle head. For this purpose a siphon tube 143 has its lower end immersed in the lubricant within the pocket 142 (Fig. 15). Tube 143 passes through the partition wall 27a and then longitudinally of the chamber 12a in the overhanging arm 12 (see Fig. 4). At its right end (Fig. 1) the tube 143 is connected into a fitting 144 which also has connected thereto a downwardly extending tube 145 forming the opposite leg of the siphon. This siphon is of an automatic priming type and may suitably be of the character disclosed in the application of John G. Attwood, Serial No. 472,488, filed December 1, 1954, now Patent No. 2,780,192, granted February 5, 1957. It includes a cup 146 carried at the upper end of a vertical tube forming an extension of the leg 145 above the fitting 144. This cup is arranged to receive lubricant which is collected by a rib, similar to the rib 86 shown in Fig. 1, at the top of the vertical standard. The construction of the siphon as a whole is such, as explained in said Attwood application, as to insure prompt and automatic priming thereof whenever the machine is put into operation. By appropriate restriction of the passages at the various points of the siphon which have access to air, it is prevented from becoming air-locked and serves to retain the siphon tube appropriately filled with lubricant to insure its proper operation, even though the lubricant in the pocket of the needle head may drop below the inlet of the siphon.

To enable the operator to determine at all times the

level of the lubricant within the reservoir 15, an oil gauge 147 is provided at a suitable height along the front wall of the vertical standard 11. This oil gauge is controlled by a float 148, preferably formed of cork, mounted on the end of a horizontally extending arm of a lever 149, as best shown in Figs. 1, 5, and 6. Lever 149 is rockably mounted upon a pin 149a which extends inwardly from a disc 149b having a screw stud 149c by which it is secured to the forward wall of the reservoir. Pin 149a extends from the disc 149 at a point eccentric to the axis of the screw stud 149c and thus enables appropriate adjustment of the height of the pin to enable calibration of the gauge. At the end of the lever 149 which extends into the vertical standard there is attached thereto the lower end of a link 150, the upper end of which is connected with an arm 151 rockably mounted within the housing of the gauge. An upwardly extending pointer 152 carried by the arm 151 adjacent its pivot cooperates with suitable indicia on the face of the gauge to indicate the height of the lubricant within the reservoir 15. When the level of the lubricant is low additional lubricant may be supplied through a fitting 153 at the top of the overhanging arm 12, which is normally closed by a cover 154 suitably attached to the fitting for pivotal movement thereon. The lubricant so introduced passes through the chamber 12b of the overhanging arm and descends into the reservoir at the bottom of the frame.

Means are provided for delivering lubricant from the supply in the main reservoir 15 to various bearing surfaces within the base of the machine. For the purpose of lubricating the bearings for the main shaft 50, and certain parts driven thereby, this shaft is hollow and provided with a bore 160 (Fig. 6) into which is fitted, at the end of the shaft within the vertical standard, a plug 161 having a tapered opening. Some of the lubricant mist within the vertical standard, on dripping back to the main reservoir, is caught by a member 162 secured to the bottom plate 14 of the reservoir by screws 163 (Figs. 1 and 32). Member 162 has a laterally extending portion which collects the lubricant and delivers it to a downwardly extending point 164 which is disposed adjacent to the opening in the plug 161. The collected lubricant thus drips into the bore of the shaft 50 and, by virtue of the tapered opening in the plug 161, is forced toward the left (Fig. 1) along the bore. Radial openings in the shaft 50 aligned with various bearing surfaces to be lubricated serve to deliver the lubricant to those surfaces.

The gears 48 and 49, through which the hook shaft 45 is driven, are lubricated by virtue of the fact that gear 49 is partially immersed in the lubricant within the main reservoir. The hook shaft as shown in Fig. 30 extends through the left wall of the reservoir and projects into the reservoir to a substantial extent. Adjacent its inner end it is journaled in a bushing 165 carried by a wall or partition 166 which extends downwardly from the work supporting surface of the base. This wall or partition does not extend completely across the width of the reservoir, but is of sufficient width to confine any spray generated by the gear 49 to the region at the left of the partition. This prevents the undesirable delivery of lubricant to the devices, now to be described, which serve to supply lubricant to the raceway of the hook.

The means for delivering lubricant to the hook raceway involves a capillary delivery path of variable length. In this respect it operates on the same principle as the arrangement disclosed in the Attwood et al. application, Serial No. 474,142, filed December 9, 1954, now Patent No. 2,863,412, granted December 9, 1958. However, in accordance with the present invention certain improvements have been incorporated in the system. The improved construction utilizes a disc-like wick member 167 which is at all times partially immersed in the lubricant within the reservoir 15. Element 167 is formed of felt or other suitable capillary material and carries a metal

disc 167a on each face, these discs being connected by a hub or short sleeve 167b. The latter is mounted on a lateral extension 168a of an arm 168 and is retained on the extension by a spring washer 167c (Fig. 33). Arm 168 has another laterally extending arm 168b which is journaled in aligned openings provided in a channel-like bracket 169 and is retained in the bracket by a spring washer 168c cooperating with a groove near the end of extension 168b. Bracket 169 has a downwardly extending shank provided with a vertically elongated slot 169a arranged to receive a screw 170 (Fig. 31) for attachment of the bracket to a wall of the reservoir. The arrangement is such that the height of the bracket may be varied to a limited extent.

A coil spring 171 is mounted around the extension 168b between the inwardly extending arms of bracket 169. One end 171a of the spring is inserted in an opening 169b in the bracket, while a portion 171b at the opposite end of the spring cooperates with the under surface of the arm 168 to urge the same upwardly. This carries the disc 167 into engagement with the periphery of a wick-like element 172 preferably formed of felt and secured by a suitable adhesive or the like to a strip metal supporting element 173. The latter is bent into the configuration best illustrated in Fig. 33 and the arrangement is such that the element 172 does not describe a complete circle about the member 173. A gap 174 is provided between two portions of the encircling part of the element 172. Adjacent this gap the element has connected with one end thereof an inward extension 172a carrying concentrically within the interior of the support member 173 an annular portion 172b (Fig. 30). This is also adhesively secured to the adjacent surface of member 173. Within the central opening of the member 173 is mounted a disc 175, the inner face of which is in contact with the annular portion 172b of wick member 172. Disc 175 is suitably secured to the member 173. The arrangement is such that the end of the hook shaft 45 fits into the opening at the center of the portion 172b of element 172 and its outer end surface is in engagement with the inner surface of disc 175. Axial movement of the shaft 45 is prevented by the gear 48 and a collar 45b, secured to the shaft within the reservoir.

Aligned with the hook shaft is a shaft 176 carried by a bearing sleeve 177 (Fig. 30) extending through a partition wall within the reservoir 15. Secured to the left end of the shaft 176 (Figs. 30 and 33) is a disc 178 having a hub 178a mounted on the shaft and secured thereto by a set screw 178c. A pin 178d extending laterally from the disc 178 cooperates with a notch 175a in the disc 175 so that the latter, together with the wick element 172, will be turned as the shaft 176 is turned in the manner to be explained. Shaft 176 has an axial bore in its left end in which is slidably mounted a pin 179, this pin being urged outwardly by a spring 180 within the bore of the shaft. The outer end of the pin 179 is rounded or of bullet form and cooperates with a central spherical depression 175b in the disc 175. This arrangement is such that the spring 180 urges the disc 175 against the adjacent end of the hook shaft 45. A spring 181 surrounding the hook shaft, adjacent its end, serves to urge a sealing ring 182 toward the right into engagement with the annular portion 172b of element 172, the axial force exerted by the spring 181 being somewhat less than that exerted by spring 180. Sealing ring 182 serves to restrict to a minimum the flow of air to the annular portion 172b of the wick element and thus prevents the system from becoming air-locked.

The construction as a whole is such that lubricant picked up by the disc 167 is transferred to the wick element 172 at the point of contact of these members and is carried by capillary action around to the inwardly extending portion 172a of the wick element and to the annular portion 172b thereof. A suitable amount of

lubricant is in this way delivered to the inner face of the disc 175 from which it may be readily picked up by a helical groove 183 provided in the adjacent end face of the hook shaft 45 as the latter rotates. The inner end 5 of the helical groove 183 communicates with the bore of the hook shaft and thus serves to pump a limited amount of oil into the bore. Within the latter there is preferably provided a pin 45a (Fig. 30) which fits snugly within the bore and is arranged to turn with the shaft. A longitudinally extending slot 45c in the surface of the pin 45a provides a channel of limited cross-section for the delivery of lubricant from the right end of the hook shaft toward the left for ultimate delivery to the raceway of the hook. For further details as to the manner in which the lubricant is delivered to the hook raceway reference may be had to the above mentioned Attwood et al. application.

It will be appreciated that the rate of delivery of lubricant to the bore of the hook shaft may be varied by varying the point of contact between the disc 167 and element 172 so as to alter the length of the capillary path to be traversed by the lubricant in reaching the surface of the disc 175. For this purpose provision is made for turning the shaft 176 and, through the action of pin 178d, the wick element 172. Thus, there is secured to the right end of the shaft 176 a gear 184 having a hub 184a secured by a set screw 184b to a reduced portion of shaft 176. The teeth of the gear 184 may suitably be formed by a simple stamping operation. Cooperating with the gear 184 is a similarly formed gear 185 mounted to turn about an axis at right angles to the axis of the shaft 176. Gear 185 has a hub 185a secured by a set screw 185b to a stud 186 (Figs. 1 and 30) journaled in the front wall of the reservoir 15 and accessible at the outer surface of said wall for turning by hand. As shown, the stud may suitably be provided with a slot adapted to receive a screw driver. It may, however, be provided with a knurled head, if desired. Appropriate indicia may be provided on the outer surface of the lubricant reservoir, adjacent the head of the stud, to indicate its setting. To limit the extent of rotation of the stud 186 and gear 185, the latter has a non-toothed portion 185c which when brought into cooperation with the teeth of the gear 185, upon rotation of gear 185 in either direction, will serve to lock the gears against further rotation in the same direction. The arrangement of the portion 185c is such that it will prevent the turning of the element 172 into a position in which the gap 174 is brought directly over the disc 167.

It is believed that the operation of the various devices embodied in the machine, and particularly the lubrication system thereof, will be clear from the foregoing detailed description of the several parts. Also, it will be understood that various changes may be made in the form and arrangement of certain parts within the scope of the invention as defined by the appended claims.

What is claimed is:

1. A lockstitch sewing machine comprising a frame having a work supporting base, a vertical standard and an overhanging arm extending laterally from said standard and terminating in a head disposed over said base, stitch forming devices comprising a reciprocable needle carrying bar in said head and a rotary hook in said base, a horizontally disposed shaft carrying said hook and arranged to operate the same, said hook having a raceway and said shaft having a bore communicating with said raceway, a main lubricant reservoir in said base adapted to retain lubricant at a level below said bore in said shaft, capillary means in said base for delivering a regulated quantity of lubricant directly from said reservoir to the bore of said shaft for delivery to the raceway of said hook, means for impelling lubricant from said reservoir and delivering the same through said standard and arm and into said head for lubricating parts therein including 60 said needle bar, said last mentioned means comprising 65 70 75

capillary means for lifting a restricted part of the impelled lubricant and delivering the same to parts in said head, and means for returning excess lubricant from said head to said reservoir

2. A lockstitch sewing machine comprising a frame having a work supporting base, a vertical standard and an overhanging arm extending laterally from said standard and terminating in a head disposed over said base, stitch forming devices comprising a reciprocable needle carrying bar in said head and a rotary hook in said base, a horizontally disposed shaft carrying said hook and arranged to operate the same, said hook having a raceway and said shaft having a bore communicating with said raceway, a pair of interconnected drive shafts, one extending longitudinally of said arm and the other extending longitudinally of said base, connections from said shafts to said needle bar and to said hook carrying shaft for driving the same, a main lubricant reservoir in said base adapted to retain lubricant at a level below said bore in said shaft, capillary means in said base for delivering a regulated quantity of lubricant directly from said reservoir to the bore of said shaft for delivery to the raceway of said hook, said connections for driving said hook carrying shaft being partially immersed in the lubricant in said reservoir, means for impelling lubricant from said reservoir and delivering the same through said standard and arm and into said head for lubricating the driving connections for said needle bar, said last mentioned means comprising capillary means for lifting a restricted part of the impelled lubricant and delivering the same to said driving connections for said needle bar, and means for returning said excess lubricant from said head to said reservoir.

3. A lockstitch sewing machine comprising a frame having a work supporting base, a vertical standard and an overhanging arm extending laterally from said standard and terminating in a head disposed over said base, stitch forming devices comprising a reciprocable needle carrying bar in said head and a rotary hook in said base, horizontally disposed shaft carrying said hook and arranged to operate the same, said hook having a raceway, a main lubricant reservoir in said base, adapted to retain lubricant at a level below said shaft, means in said base for lifting and delivering a regulated quantity of lubricant directly from said reservoir to said shaft for delivery therewith to the raceway of said hook, said means comprising relatively adjustable wick means adapted upon adjustment to vary the quantity of lubricant delivered to said raceway, means for impelling lubricant from said reservoir and delivering the same through said standard and arm and into said head for lubricating parts therein including said needle bar, said last mentioned means comprising capillary means for lifting a restricted part of the impelled lubricant and delivering the same to parts in said head, and means for returning excess lubricant from said head to said reservoir.

4. A sewing machine comprising a frame having a work supporting base, a vertical standard and an overhanging arm extending laterally from said standard and terminating in a head disposed over said base, stitch forming devices comprising a needle carrying bar mounted for reciprocation in said head and loop taking means in said base, means comprising a shaft journaled in said arm for operating said stitch forming devices, said means having a plurality of bearing surfaces within said arm and in said base, a main lubricant reservoir in said base, means in said frame for impelling lubricant from said reservoir through said standard and arm to said head, means for storing a portion of the lubricant so impelled and delivering the same into said head for lubricating the parts therein, said last mentioned means comprising a storage wick in said arm arranged to receive impelled lubricant constantly during the operation of the machine and wick means normally connected in series with said storage wick for delivering lubricant to parts in said head, and means

for disconnecting a portion of said wick means from another portion thereof at a point within said head and thereby interrupting the delivery of lubricant through said wick means to said parts in said head, said storage wick being arranged to deliver lubricant to one of said bearing surfaces which is in said arm, even when such portions of said wick means are disconnected.

5. A sewing machine comprising a frame having a work supporting base, a vertical standard and an overhanging arm extending laterally from said standard and terminating in a head disposed over said base, stitch forming devices comprising a needle carrying bar mounted for reciprocation in said head and loop taking means in said base, means for operating said stitch forming devices, said means having a plurality of bearing surfaces within said head, a main lubricant reservoir in said base, means in said frame for dispersing lubricant from said reservoir as a mist in said standard, means for collecting a portion of the lubricant in said mist and delivering the same to said head for lubricating the bearing surfaces therein, said last mentioned means comprising a plurality of normally engaged wick means in series extending into said head, one of said wick means being arranged to receive and store within said overhanging arm a limited amount of lubricant from said mist, means for returning to said reservoir excess lubricant delivered to said one of said wick means, and means for disengaging adjacent ones of said wick means at a point within said head and thereby interrupting the delivery of lubricant through said wick means in series to said bearing surfaces in said head without interrupting the delivery of lubricant from said one of said wick means to points outside of said head.

6. A sewing machine comprising a frame having a work supporting base, a vertical standard and an overhanging arm extending laterally from said standard and terminating in a head disposed over said base, a drive shaft extending longitudinally of said arm having a bearing therein adjacent said head, stitch forming devices comprising a needle carrying bar mounted for reciprocation in said head and loop taking means in said base, means for operating said stitch forming devices, said means having a plurality of bearing surfaces within said head, a main lubricant reservoir in said base, means in said frame for dispersing lubricant from said reservoir as a mist in said standard, means for collecting a portion of the lubricant in said mist and delivering the same to said bearing for said shaft and to said bearing surfaces within said head for lubricating the bearing surfaces therein, said last mentioned means comprising a plurality of wick means in series, and means within said head for interrupting the delivery of lubricant through said wick means in series to said bearing surfaces in said head without interrupting the delivery of lubricant from said wick means to said bearing for said shaft.

7. A sewing machine comprising a frame having a work supporting base, a vertical standard and an overhanging arm extending laterally from said standard and terminating in a head disposed over said base, a drive shaft extending longitudinally of said arm and having a bearing therein adjacent said head, stitch forming devices comprising a needle carrying bar mounted for reciprocation in said head and loop taking means in said base, means for operating said stitch forming devices, said means having a plurality of bearing surfaces within said head, a main lubricant reservoir in said base, means in said frame for dispersing lubricant from said reservoir as a mist in said standard, means for collecting a portion of the lubricant in said mist and delivering the same to said bearing for said shaft and to said bearing surfaces within said head for lubricating the bearing surfaces therein, said last mentioned means comprising a plurality of wick means in series, means cooperating with said wick means for preventing delivery of excess lubricant into said head and for returning excess lubricant to said reservoir, and means within said head for interrupting the

delivery of lubricant through said wick means in series to said bearing surfaces in said head without interrupting the delivery of lubricant from said wick means to said bearing for said shaft.

8. A sewing machine comprising a frame having a work supporting base, a vertical standard and an overhanging arm extending laterally from said standard and terminating in a head disposed over said base, stitch forming devices comprising a needle carrying bar mounted for reciprocation in said head and loop taking means in said base, means for operating said stitch forming devices, said means having a plurality of bearing surfaces within said head, a main lubricant reservoir in said base, means in said frame for dispersing lubricant from said reservoir as a mist in said standard, means for collecting a portion of the lubricant in said mist and delivering the same to said head for lubricating parts therein, said last mentioned means comprising a plurality of wick means in series, spring means normally urging one of said wick means into engagement with another, and a manually operable cam for forcing said one of said wick means out of engagement with the other, thereby interrupting the delivery of lubricant through said wick means in series.

9. A sewing machine comprising a frame having a work supporting base, a vertical standard and an overhanging arm extending laterally from said standard and terminating in a head disposed over said base, stitch forming devices comprising a needle carrying bar mounted for reciprocation in said head and loop taking means in said base, means for operating said stitch forming devices, said means having a plurality of bearing surfaces within said head, a main lubricant reservoir in said base, means in said frame for dispersing lubricant from said reservoir as a mist in said standard, means for collecting a portion of the lubricant in said mist and delivering the same to said head for lubricating parts therein, said last mentioned means comprising a plurality of wick means in series, said wick means comprising one member in said head arranged to deliver lubricant to bearing surfaces therein and a second member extending from said arm into said head and normally engaged with said one member, an opening in said head enabling hand lubrication of said one member, and manually adjustable means normally concealing said opening but operable to expose the same and simultaneously shift said second member out of engagement with said first member, thereby interrupting the delivering of lubricant through said wick means in series.

10. A sewing machine comprising a frame having a work supporting base, a vertical standard and an overhanging arm extending laterally from said standard and terminating in a head disposed over said base, stitch forming devices comprising a needle carrying bar mounted for reciprocation in said head and loop taking means in said base, means for operating said stitch forming devices, said means having a plurality of bearing surfaces within said head, a main lubricant reservoir in said base, means in said frame for dispersing lubricant from said reservoir as a mist in said standard, means for collecting a portion of the lubricant in said mist and delivering the same to said head for lubricating parts therein, said last mentioned means comprising a plurality of wick means in series, one of said wick means extending from said arm into said head and another of said wick means being disposed in said head and arranged to deliver lubricant to bearing surfaces therein, means for normally yieldingly urging said wick means into engagement with each other for the transmission of lubricant therebetween, and manually adjustable means for camming said wick means apart and thereby interrupting the automatic delivery of lubricant through said wick means in series, said manually adjustable means enabling hand lubrication of the bearing surfaces within said head when said automatic delivery of lubricant is interrupted.

11. A sewing machine comprising a frame having a work supporting base, a vertical standard and an over-

hanging arm extending laterally from said standard and terminating in a head disposed over said base, stitch forming devices comprising a needle carrying bar mounted for reciprocation in said head and loop taking means in said base, means for operating said stitch forming devices, a plurality of bearing surfaces within said head for said means, a main lubricant reservoir in said base, means in said frame for dispersing lubricant from said reservoir as a mist in said standard, means for collecting a portion of the lubricant in said mist and delivering the same to said head for lubricating parts therein, said last-mentioned means including wicks, means for restricting the amount of lubricant so delivered into said head and for returning the excess of the collected lubricant which is not delivered into said head directly from said overhanging arm to said reservoir, said parts in said head serving to create a lubricant mist in said head, and capillary means in said head arranged to collect lubricant from the mist therein and deliver the same to said needle bar at an elevated point thereon.

12. A sewing machine comprising a frame having a work supporting base, a vertical standard and an overhanging arm extending laterally from said standard and terminating in a head disposed over said base, said head providing a substantially lubricant-tight enclosure but having at least one opening through which lubricant may escape therefrom, stitch forming devices comprising a needle carrying bar mounted for reciprocation in said head and loop taking means in said base, means for operating said stitch forming devices, a plurality of bearing surfaces within said head for said means, a main lubricant reservoir in said base, means in said frame for dispersing lubricant from said reservoir as a mist in said standard, means for collecting a portion of the lubricant in said mist and delivering the same to said head for lubricating parts therein, said last-mentioned means including wicks, said parts serving to create a lubricant mist in said head, capillary means in said head arranged to collect lubricant from the mist in said head, said capillary means extending upwardly along a wall of said head and along at least one side of said opening, and means arranged to receive lubricant from said capillary means and deliver the same to certain of said bearing surfaces in said head, said last mentioned means being arranged to prevent the discharge of lubricant mist through said opening in said head.

13. A sewing machine comprising a frame having a work supporting base, a vertical standard and an overhanging arm extending laterally from said standard and terminating in a head disposed over said base, said head having an elongated opening in a wall thereof through which a moving part extends, stitch forming devices comprising a needle carrying bar mounted for reciprocation in said head and loop taking means in said base, means for operating said stitch forming devices, a plurality of bearing surfaces within said head for said means, a main lubricant reservoir in said base, means in said frame for dispersing lubricant from said reservoir as a mist in said standard, means for collecting a portion of the lubricant in said mist and delivering the same to said head for lubricating parts therein, said last-mentioned means including wicks, said parts serving to create a lubricant mist in said head, capillary means in said head extending vertically along said wall thereof and arranged to collect lubricant from the mist in said head, a bracket in said head for retaining said capillary means against said wall, said bracket having an inclined shelf portion extending across the top of said opening, and further capillary means carried by said shelf and arranged to receive lubricant from said first mentioned capillary means and deliver said lubricant to certain of said bearing surfaces.

14. A sewing machine comprising a frame having a work supporting base, a vertical standard and an overhanging arm extending laterally from said standard and

terminating in a head disposed over said base, a shaft extending longitudinally of said arm and into said head, a bearing for said shaft adjacent said head, stitch forming devices comprising a needle carrying bar mounted for reciprocation in said head and loop taking means in said base, connections from said shaft for operating said needle carrying bar, said bar and the operating connections therefor having a plurality of bearing surfaces within said head, a main lubricant reservoir in said base, means in said frame for dispersing lubricant from said reservoir as a mist in said standard, means for collecting a portion of the lubricant in said mist and delivering the same to said head for lubricating said bearing surfaces therein, said last mentioned means comprising a lubricant storing wick member arranged to receive lubricant from said mist and deliver a portion of the same directly to said bearing for said shaft, and wick means connected with said wick member and arranged to deliver lubricant therefrom into said head, said wick means comprising a pair of wick elements yieldingly urged into contact within said head, and cam means for separating said wick elements to interrupt the delivery of lubricant from one to the other.

15. A sewing machine comprising a frame having a work supporting base, a vertical standard and an overhanging arm extending laterally from said standard and terminating in a head disposed over said base, a shaft extending longitudinally of said arm and into said head, a bearing for said shaft adjacent said head, stitch forming devices comprising a needle carrying bar mounted for reciprocation in said head and loop taking means in said base, means for operating said stitch forming devices, said means having a plurality of bearing surfaces within said head, a main lubricant reservoir in said base, means in said frame for dispersing lubricant from said reservoir as a mist in said standard, means comprising a tube extending longitudinally of said arm and having an open trough within said standard for collecting a portion of the lubricant in said mist and delivering the same to said head for lubricating said bearing surfaces therein, a lubricant storing wick member within said tube, a wall in the path of said wick member forming a dam over which said member is passed, an opening in advance of said wall through which lubricant may be discharged from said tube, a portion of said wick member beyond said wall serving to deliver lubricant to said bearing for said shaft, and wick means arranged to receive lubricant from said storing wick member and deliver the same by capillary action into said head.

16. A sewing machine comprising a frame having a work supporting base, a vertical standard and an overhanging arm extending laterally from said standard and terminating in a head disposed over said base, said base, standard and arm providing intercommunicating enclosures, stitch forming devices comprising a needle carrying bar mounted for reciprocation in said head and loop taking means in said base, means for operating said stitch forming devices, said means having a plurality of bearing surfaces within said head, a main lubricant reservoir in said base, means in said frame for dispersing lubricant from said reservoir as a mist in said standard, means for collecting a portion of the lubricant in said mist and delivering the same to said head for lubricating the bearing surfaces therein, said last-mentioned means including wicks, moving parts in said head serving to create a lubricant mist therein, said head having an opening through the wall thereof arranged to accommodate a moving part projecting from said head, hood means extending outwardly from said head over said moving part arranged to collect lubricant discharged through said opening, and means comprising a capillary member for delivering said lubricant directly into said overhanging arm and thereby returning said lubricant to said reservoir.

17. A sewing machine comprising a frame having a work supporting base, a vertical standard and an over-

hanging arm extending laterally from said standard and terminating in a head disposed over said base, stitch forming devices comprising a needle carrying bar mounted for reciprocation in said head and loop taking means in said base, means for operating said stitch forming devices, said means having a plurality of bearing surfaces within said head, a main lubricant reservoir in said base, means in said frame for dispersing lubricant from said reservoir as a mist in said standard, means for collecting a portion of the lubricant in said mist and delivering the same to said head for lubricating the bearing surfaces therein, said last-mentioned means including wicks, moving parts in said head serving to create a lubricant mist therein, said head having an opening through the wall thereof arranged to accommodate a moving part projecting from said head, hood means extending outwardly from said head over said moving part arranged to collect lubricant discharged through said opening, and means for returning said lubricant to said reservoir, said last-mentioned means comprising capillary means in said hood for collecting the lubricant discharged through said opening, and wick means arranged to receive the so collected lubricant and deliver the same to said arm for return to said reservoir.

18. A sewing machine comprising a frame having a work supporting base, a vertical standard and an overhanging arm extending laterally from said standard and terminating in a head disposed over said base, stitch forming devices comprising a needle carrying bar mounted for reciprocation in said head, a needle carried by said bar, means comprising an arm extending through an elongated opening in a wall of said head and oscillatable within said opening for guiding and imparting a take-up action to thread carried by said needle, means comprising a rotary shaft carried by said arm extending into said head and a pitman extending downwardly from said shaft within said head for operating said bar and said take-up arm, said means having a plurality of bearing surfaces within said head, a main lubricant reservoir in said base, means in said frame for dispersing lubricant from said reservoir as a mist in said standard, means for collecting a portion of the lubricant in said mist and delivering the same to said head for lubricating said bearing surfaces therein, said last-mentioned means including wicks, said operating means for said needle carrying bar serving to create a lubricant mist within said head, and means carried by the upper end of said pitman having a sloping circumferential surface of increasing radius in a direction away from the vertical plane in which said take-up arm swings arranged to direct the lubricant which collects thereon from said lubricant mist away from said opening.

19. A sewing machine comprising a frame having a work supporting base, a vertical standard and an overhanging arm extending laterally from said standard and terminating in a head disposed over said base, stitch forming devices comprising a needle carrying bar mounted for reciprocation in said head, a needle carried by said bar, means comprising an arm extending through an elongated opening in a wall of said head and oscillatable within said opening for guiding and imparting a take-up action to thread carried by said needle, means comprising a rotary shaft carried by said arm extending into said head and a pitman extending downwardly from said shaft within said head for operating said bar and said take-up arm, said means having a plurality of bearing surfaces within said head, means for supplying lubricant to the bearing surfaces for said operating means for the needle carrying bar, said operating means for said needle carrying bar serving to create a lubricant mist within said head, and means carried by the upper end of said pitman having a sloping circumferential surface of increasing radius in a direction away from the vertical plane in which said take-up arm swings arranged to direct the lubricant which collects thereon from said lubricant mist away from said opening.

20. A lockstitch sewing machine having a frame pro-

viding a work supporting base, a lubricant reservoir in said base, a rotary hook carried by said base outwardly of said reservoir, said hook having a rotary component provided with a raceway and a stationary component provided with ribs cooperating with said raceway, a horizontally disposed hook shaft on which said rotary component is mounted for rotation of the latter, said shaft having an axial bore and extending into said reservoir, a rotary drive shaft in said base extending into said reservoir, connections between said hook shaft and drive shaft with said reservoir for operating said hook shaft, and means in said reservoir for delivering lubricant to the bore of said hook shaft for delivery to said raceway, said means comprising a pair of rotary disc-like elements having their peripheries in frictional engagement for rotation of one of said elements by the other, the peripheral portions of said elements being of porous construction and adapted for transmission of oil by capillary action, one of said elements being partially immersed in the lubricant in said reservoir and arranged to lift lubricant by capillary action and transfer the same to the other of said elements at the point of contact between said elements, means for delivering lubricant to the bore of said hook shaft from a portion of said other of said elements spaced from the point thereon which is in contact with said one of said elements, and means for rotating said elements to vary the distance from said portion of said other of said elements to its point of contact with said one of said elements.

21. A lockstitch sewing machine having a frame providing a work supporting base, a lubricant reservoir in said base, a rotary hook carried by said base outwardly of said reservoir, said hook having a rotary component provided with a raceway and a stationary component provided with ribs cooperating with said raceway, a horizontally disposed hook shaft on which said rotary component is mounted for rotation of the latter, said shaft having an axial bore and extending into said reservoir, a rotary drive shaft in said base extending into said reservoir, connections between said hook shaft and drive shaft within said reservoir for operating said hook shaft, and means in said reservoir for delivering lubricant to the bore of said hook shaft for delivery to said raceway, said means comprising a pair of rotary disc-like elements at different elevations in said reservoir having their peripheries in frictional engagement for rotation of one of said elements by the other, an arm pivotally mounted in said reservoir and providing an axis for rotation thereon of one of said elements, a spring urging said arm upwardly to hold said one element yieldingly against the other, the peripheral portions of said elements being of porous construction and adapted for transmission of oil by capillary action, said one of said elements being partially immersed in the lubricant in said reservoir and arranged to deliver lubricant by capillary action to the other of said elements at the point of contact between said elements, means for delivering lubricant to the bore of said hook shaft from a portion of said other of said elements spaced from the point thereon which is in contact with said one of said elements, and means for rotating said elements to vary the distance from said portion of said other of said elements to its point of contact with said one of said elements.

22. A lockstitch sewing machine having a frame providing a work supporting base, a lubricant reservoir in said base, a rotary hook carried by said base outwardly of said reservoir, said hook having a rotary component provided with a raceway and a stationary component provided with ribs cooperating with said raceway, a horizontally disposed hook shaft on which said rotary component is mounted for rotation of the latter, said shaft having an axial bore and extending into said reservoir, a rotary drive shaft in said base extending into said reservoir, connections between said hook shaft and drive shaft within said reservoir for operating said hook shaft, and means

in said reservoir for delivering lubricant to the bore of said hook shaft for delivery to said raceway, said means comprising a pair of rotary disc-like elements having their peripheries in frictional engagement for rotation of one of said elements by the other, the peripheral portions of said elements being of porous construction and adapted for transmission of oil by capillary action, one of said elements being partially immersed in the lubricant in said reservoir and arranged to lift lubricant by capillary action and transfer the same to the other of said elements at the point of contact between said elements, means for delivering lubricant to the bore of the hook shaft from a portion of said other of said elements spaced from the point thereon which is in contact with said one of said elements, and means for rotating said other of said elements to vary the distance from said portion thereof to its point of contact with said one of said elements, said last recited means comprising a pair of intermeshing spur gears mounted for rotation about axes at right angles to each other, and means on said gears for limiting the extent of rotation thereof in either direction.

23. A lockstitch sewing machine having a frame providing a work supporting base, a lubricant reservoir in said base, a rotary hook carried by said base outwardly of said reservoir, said hook having a rotary component provided with a raceway and a stationary component provided with ribs cooperating with said raceway, a horizontally disposed hook shaft on which said rotary component is mounted for rotation of the latter, said shaft having an axial bore and extending into said reservoir, a rotary drive shaft in said base extending into said reservoir, connections between said hook shaft and drive shaft within said reservoir for operating said hook shaft, and means in said reservoir for delivering lubricant to the bore of said hook shaft for delivery to said raceway, said means comprising a pair of rotary disc-like elements having their peripheries in frictional engagement for rotation thereof in unison, the peripheral portions of said elements being adapted for transmission of oil by capillary action, one of said elements being mounted on said hook shaft and rotatable relative thereto, the other of said elements being mounted on a journal beneath and parallel with said hook shaft and yieldingly urged toward the latter, said other element being partially immersed in the lubricant in said reservoir and arranged to lift lubricant by capillary action and transfer the same to said one of said elements at the point of contact between said elements, means for delivering lubricant to the bore of the hook shaft from a portion of said one of said elements spaced from the point thereon which is in contact with said other of said elements, and means for rotating said one of said elements to adjust the same which comprises a stub shaft aligned with said hook shaft and a stud at right angles thereto, intermeshing spur gears carried by said stub shaft and stud, respectively, and means on said gears for limiting the rotation thereof.

24. A lockstitch sewing machine having a frame providing a work supporting base, a lubricant reservoir in said base, a rotary hook carried by said base outwardly of said reservoir, said hook having a rotary component provided with a raceway and a stationary component provided with ribs cooperating with said raceway, a horizontally disposed hook shaft on which said rotary component is mounted for rotation of the latter, said shaft having an axial bore and extending into said reservoir, a rotary drive shaft in said base extending into said reservoir, gears within said reservoir for connecting said drive shaft with said hook shaft, at least one of said gears being partially immersed in the lubricant in said reservoir and serving to create a lubricant spray therein, and means in said reservoir for delivering lubricant to the bore of said hook shaft for delivery to said raceway, said means comprising a pair of rotary disc-like elements having their peripheries in frictional engagement for rotation of one of said elements

by the other, the peripheral portions of said elements being of porous construction and adapted for transmission of oil by capillary action, one of said elements being partially immersed in the lubricant in said reservoir and arranged to lift lubricant by capillary action and transfer the same to the other of said elements at the point of contact between said elements, means for delivering lubricant to the bore of said hook shaft from a portion of said other of said elements spaced from the point thereon which is in contact with said one of said elements, means for turning said other of said elements for varying the distance between said portion and said point, and a partition within said reservoir between said gears and said disc-like elements serving to shield the latter from the spray generated by said gears.

UNITED STATES PATENT OFFICE
CERTIFICATE OF CORRECTION

Patent No. 2,977,910

April 4, 1961

John N. Covert

It is hereby certified that error appears in the above numbered patent requiring correction and that the said Letters Patent should read as corrected below.

In the grant, line 1, name of inventor, for "John N. Cobert" read -- John N. Covert --; column 7, line 3, for "overhainging" read -- overhanging --; line 35, for "oprtion" read -- portion --; column 13, line 2, for "delivering" read -- delivering --; line 4, after "reservoir" insert a period; same column 13, line 15, for "asid" read -- said --.

Signed and sealed this 21st day of November 1961.
